poration, a corporation of Delaware

Application October 25, 1932, Serial No. 638,461

2 Claims. (CL. 62—4)

This invention relates to refrigeration and/or starting controls for electric motors. Certain types of refrigerating systems operate intermittently, the temperatures are maintained the object to be cooled by starting and stopping the refrigerating system to produce refrigeration intermittently. Other types of refrigerating systems operate substantially continuously and some type of throttling or governing device is provided for varying the refrigerating capacity of the system in accordance with refrigeration demands in such a manner that the desired temperatures are maintained in the object to be cooled. In either case, the refrigerating system is stopped periodically for adjustments, defrosting, or for transportation of the system. The system, if it be of the compressor-condenser-evaporator type, is generally driven by an electric motor and it is necessary provide a control for the electric current to the motor so that it may start properly and unwillingly. It is among the objects of this invention to provide a starting control for an electric motor which is capable of governing the current flowing to the motor efficiently and with the likelihood of failure, regardless of unfavorable operating conditions and varying line voltages.

Further objects and advantages of the present invention will be apparent from the following description, reference being had to the accompanying drawings, wherein a preferred form of the present invention is clearly shown.

In the drawings:

Fig. 1 is a diagrammatic showing of a refrigerating system embodying features of this invention;

Fig. 2 is a diagrammatic showing of a slightly modified form of the invention;

Fig. 3 is a side elevational view of a unitary assembly containing the motor starting controls, the view showing the assembly on a base with the cover removed;

Fig. 4 is a top plan shown as looking down upon the top edge of Fig. 3;

Fig. 5 is a cross sectional view taken along the line 5—5 of Fig. 3;

Fig. 6 is a cross sectional view taken along the line 6—6 of Fig. 3; and

Fig. 7 is a cross sectional view taken along the line 7—7 of Fig. 3.

A refrigerating system embodying features of this invention may include a compressor 10 delivering refrigerant to a condenser 11 from hence the refrigerant flows to the evaporator

12 and returns through the return line 13 to the compressor 10. Between the condenser 11 and the evaporator 12 is an expansion device 14 which maintains the necessary pressure differential between the condenser 11 and the evaporator 12. Preferably this refrigerating system is of the substantially continuously operating type in which the parts are so co-related with the refrigeration demands of the object to be cooled that the system inherently maintains the desired temperature in the object notwithstanding variations in the atmospheric temperature. Such a system includes a continuously open expansion device in the form of a fixed elongated orifice. If the system should be stopped for any reason, the pressures within the refrigerating system equalize within a relatively short time such as within one quarter to one half hour. Such a system is more particularly described in the application of Andrew A. Kucher, Serial No. 599,239 filed March 20 16, 1932 to which reference is hereby made for further disclosure of such a system.

The compressor 10 is driven by an electric motor 15 which may be placed in a hermetic casting 16a with the compressor, and which may be of the split phase type having a rotor 15a, a running winding 16 and a starting winding 17. My improved control so governs the flow of current to these windings, that the current flows to both windings during the necessary normal starting period of the motor and the current is disconnected from the starting winding 17 after the termination of the normal starting period of the motor. To this end, as shown in Fig. 1, a common lead line 18 is connected to the running and starting windings at 19. Another lead line 20 is divided into a starting lead line 21 connected to the starting winding at 22 and also into a running lead line 23 connected to the running winding 16 at the point 24. An electromagnet 25 is placed in the running lead line 23 and is connected by the branches 26 and 27 in the running lead line. A shunt is placed in the running lead line so that the electromagnet 25 may be shunted out of the system, and this shunt may include a timing device 28, conveniently in the form of a bimetallic U-shaped member connected by the shunt branches 28 and 29 of the running lead line. The electromagnet 25 is provided with an armature 31 which includes means 30 or contacts 32 and 33 for opening and closing the starting lead line 21. The armature 31 can retract from the magnet 25 a sufficient distance 34, such that it is attracted to the magnet 25 in response to the starting surge current pass-

ing through the running winding 16, but the space 34 is sufficiently large that the armature 31 is not attracted to the magnet during the normal running current flowing through the running winding 16, if, for any reason, the armature 31 is permitted once to assume its retracted position.

In addition, an overload device 35 is placed in the electric circuit, so that it stops the flow of current in response to an excess current flowing to the motor for an excessive period of time. Conveniently the overload device 35 is placed in the line 20 and includes a bimetallic member 36 heated by a resistance 37 through which the current flowing from the line 20 to the motor 15 passes. The bimetallic member 36 upon being heated beyond a normal temperature by the resistance 37 causes the lever 38 to pivot about the point 39 and open the contacts 40 to stop the flow of current to the motor 15.

The operation of the system shown in Fig. 1 is as follows. When current is first caused to flow through the system, it passes through the lead line 20, the running lead line 23, the running winding 16, and the common lead line 18. At this time, the current flows through the branches 26 and 27 and the electromagnet 25. The electromagnet, in response to the starting surge current through the running winding 16, attracts the armature 31, so that it pivots about the fulcrum 41 and closes the contacts 32 and 33, thus causing current to flow through the starting lead line 21 and the starting winding 17. The starting current in passing through the timing device 28, which, in this form, is a bimetallic U-shaped member, causes it to bend to close contacts 42. When these contacts are closed, the electromagnet is shunted out of the circuit, the current flowing through the branches 29, 30, a portion of the member 28 and contacts 42. The time required for the completion of this bending action of the timing device 28 is sufficiently long, so that the contacts 42 are not closed until after the normal period of time required for the motor to start. After this period of time, the magnet 25 is shunted out of the circuit and the armature 31 retracts from the magnet 25 and opens the contacts 33 and 34, thus stopping the flow of current to the starting winding 17. Bimetallic member 28 is so calibrated, that when the starting current ceases to flow through it, it separates the contacts 42 and thus the current flows to the motor only through the lead line 20, the branches 26, 27, and the electromagnet 25, the running winding 16, and the lead line 18. Since the motor has attained speed, the current flowing through the electromagnet 25 is only the normal running current and this is insufficient to attract the armature 31 to the magnet 25 after the armature has been permitted to retract by the shunting action heretofore described. The motor continues to operate in this manner until it is stopped either by the overload device 35, by a thermostatic switch 12a or similar device which controls the refrigerating effect on the system, or by any other automatic or manual switch which may be conveniently placed in the system.

In the modification shown in Fig. 2, the refrigerating system may be identical with that shown in Fig. 1 and hence corresponding parts are given identical numbers. The motor 15 may also be identical with that shown in Fig. 1 and hence its rotor, running winding and starting winding are given identical numbers. In this modification a common lead line 18 is also provided, this being

connected to the running and starting winding at the point 19. Another lead line 20 is provided having the overload device 35 identical with that described in Fig. 1 including the bimetallic member 36 and the resistance 37, arm 38, fulcrum 39, and contacts 40. The starting line 21a and the running lead line 23a are slightly modified.

The branch 58, timing device 52 and branch 51 are parts of both the running lead line 23a and the starting lead line 21a. From the point 57a on part of the running lead line 23a includes the branch 58, electromagnet 59 and branch 55 leading to the running winding 16 at 24. Another part of the running lead line includes the contacts 53 and the branch 54. The starting lead line 21a includes the branch 60, contacts 61, 62, and the branch 63 leading to the starting winding 17 and 22.

In modification shown in Fig. 2, when the current is first introduced into the system, it flows through the lead 20, contacts 40, resistance 37, branch 58, legs 51, 56, branches 57, 58, electromagnet 59, branch 55, running winding 16, and common lead 18. The current flowing through the magnet 59 attracts the armature 64 pivoted at 65 and closes the contacts 61 and 62. Current then also flows through these contacts and the branches 60 and 63 to the starting winding 17. The current flowing through the timing device 52, which at this time includes the total current required by the starting and running windings under starting conditions is sufficient to cause the device 52 to close the contacts 53 after the normal starting period of the motor, and the device 52 is so calibrated that it will not close these contacts until the motor has started. When the contacts 53 are closed, the electromagnet 59 is shunted by a flow of current through the leg 51, contacts 53, branches 54 and 55 to the running winding 16. When this shunting action occurs, the armature 64 retracts from the magnet and opens the contacts 61 and 62, thus stopping the flow of current to the starting winding 17. The resistance of the device 52 is so calibrated that the current flowing to the running winding alone under any condition and passing through the leg 51 alone, or through both legs 51 and 56, is insufficient to maintain the device 52 in a sufficiently heated condition and, therefore the contacts 53 begin to separate as soon as the running winding is cut out. When the contacts 53 separate current flows from the line 20 through the branch 58 device 52 branches 57 and 58, electromagnet 59 and branch 55 to the running winding without closing the contacts 61, 62, since the magnet 59 is so calibrated that it cannot attract the armature 64 to it even with the highest normal running current passing through it, but can be attracted by the starting surge current flowing to the running winding. The device 52 is therefore cooled off and in readiness to initiate a starting cycle practically as soon as the previous starting cycle is terminated.

In both modifications shown in Figs. 1 and 2, the cooling action of the timing devices 28 and 52 are so calibrated with respect to the cooling action of the overload device 35, that, should the overload device 35 open the contacts 40, the timing devices 28 and 52 will have cooled and be in readiness to function before the overload device 35 has cooled and reclosed contacts 40. This is accomplished by making the members of the proper relative weight or by proper thermal insulation of the members to accomplish this result, as will be understood by those skilled in the art.

In the type of continuously operating system described in the application of Andrew A. Kucher, above referred to, it sometimes happens that the source of electric current fails temporarily either because of an electric storm or other causes, but is restored in a relatively short time. Sometimes the temporary failure is of sufficient length to permit the refrigerating system to equalize as to refrigerant pressures, but at other times the failure is of such a short duration that the refrigerant pressures cannot equalize sufficiently to unload the compressor 18 to permit the motor 15 to start. Under these conditions, when the current returns, the starting cycle will take place as usual, the current flowing through both the running winding and starting windings for the normal starting period; but since the motor is unable to start because of the high torque required, the current flowing through both windings during the starting period and the subsequent flow of current through the running winding of the stalled motor eventually causes the overload device 35 to open the contacts 40. After the contacts 40 are opened the overload device 35 starts to cool, but requires a longer length of time than is required by the timing devices 28 or 52 and hence when the overload device 35 has cooled sufficiently to close the contacts 40, the timing devices 28 and 52 are in readiness to reinitiate the starting cycle. Another starting cycle will then be completed, and if the compressor still prevents the motor from starting, another overloading action will occur and thus as many starting cycles will be repeated as required until the refrigerant pressures have equalized sufficiently to permit the motor to start. Since the system equalizes within 5 to 15 minutes, and since each overloading cycle requires from one to two minutes, the number of false starts is not excessive and will not burn out the motor.

The starting control for the motor as described in Figs. 1 and 2 conveniently may be placed in a unitary structure such as shown in Figs. 3 to 7 inclusive, in which the physical embodiment of the controls diagrammatically shown in Figs. 1 and 2 are shown. Conveniently, the starting control structures may be mounted on a base 100 made of insulating material, this base being provided with a cover 101 which may be held in place by the bolt 102 passing through both the cover and the base. The base may have protruding benches 103, 104, and 105 to which various parts of the control can be attached. Thus portions of the lead line previously described with respect to Figs. 1 and 2 may be made of brass strips and portions thereof may be made of insulated wire joining the brass strips and other members of the control.

On the bench 104 there is placed a brass strip 105 bent backwardly at 106 and provided with a contact 107 which corresponds to one of the contacts 40 shown in Figs. 1 and 2. The arm 108 may be pivoted on a pin 109, this arm corresponding to the arm 38 of Figs. 1 and 2, and the pin 109 corresponding to the fulcrum 39. This arm may be attracted by a permanent magnet 110 mounted on the backwardly offset portion 111 of the bench 104 to provide snap action, the magnet being held by a bolt 112 which may be threaded or otherwise secured in the portion 111. The arm 108 is provided with a pin 113 loosely passing through the arm 108 and provided on one side with a head and on the other with a flat metallic strip 114 with a spring 115 interposed between the plate 114 and the arm 108. The plate 114

is adapted to bridge the contact 107 and the contact 118 which is carried by another brass strip 117 mounted on the side of the bench 104. The strip 117 carries the bimetallic member 118 which engages the adjustable screw 119 carried by the arm 108. A resistance wire 120 is also secured to the strip 117 and to a brass strip 122 mounted on the bench 105a. The strip 122 carries one leg of the U-shaped bimetallic member 123 while the other leg of the bimetallic member 123 is attached to a short upward extension 124 of a metal strip 125 which is secured to the base 100. The strip 125 is provided with a wire receiving screw post 126. The strip 125 is also provided with an upward extension 127 which carries a contact 128 near the bench 103. The bench 103 also carries a brass strip 129 provided with a contact 130 at one end and with a wire terminal screw plug 131 at the other end. The contacts 128 and 130 are bridged by the contacts 132 carried at one extremity of the armature 133 which is fulcrumed on the end of the brass strip 134. Conveniently, the strip 134 is provided with one or more pins 135 which pass through holes or slots 136 in the armature 133. The other end 137 of the strip 134 acts as a stop for the armature 133 and provides the proper gap 138 from the core of the electro-magnet 139, this magnet being mounted on a magnetic L-shaped member 140 carried by the bench 105a and which carries the magnetic flux from the upper end 141 of the magnet to the proximity of the armature 133, the armature 133 being provided with a cushioning member 142. The U-shaped bimetallic member 123 is provided with a contact 142 adapted to engage a contact 143 carried by the brass strip 144 which is secured to the bench 105a and is provided with the wire terminal screw plug 146. The base 100 carries an extension 150 which has some circular channels 151 and 152 for the reception of cables as will be hereafter more fully described. The cable clamping member 153 is carried by the bolt 154 which passes through the base and engages the nut 155 underneath. A two wire cable from the source of current or main line is placed in the opening 156 and a three-way cable is placed in the opening 157 leading to the motor and forming connections with the starting and running windings and with their common lead, the ends of the wires of these cables being secured to proper places in the control apparatus in order to provide the circuits shown in either Fig. 1 or 2.

In order to connect the structures shown in Figs. 3 to 7 to obtain the circuit shown in Fig. 2, one of the wires 158 of the cable passing through 156 is connected to the post 159 carried by the strip 105. The other wire 160 of this cable is connected to the post 161. One of the wires 162 of the other cable which passes through the opening 157 is connected to the post 161. Another wire 163 of this cable is connected to the post 166, and the other wire 164 of the cable is connected to the post 131. Current flows through the wire 158, strip 105, contact 107, strip 114, contact 116, resistance 120, strip 122, bimetallic member 123, strip 125, post 126, wire 170, electromagnet 139, wire 171, post 146, and wire 163 to the running winding of the motor and returns through the common lead line 162 to the post 161, wire 160, and the main line. The electromagnet 139 is so calibrated that the starting surge current flowing through the foregoing circuit including the electromagnet 139 to the running winding causes the armature 133 to spring to its 75

upper position, thus closing the contacts 128 and 130 to close the starting lead line. The starting lead line branches from the strip 125 through the contact 128, armature 133, contact 130, strip 129, terminal 131, wire 164, to the starting winding of the motor and returns through the common lead line or wire 162 to the post 161, wire 160 to the main line. Thus the flow to the running and starting windings are substantially simultaneous, requiring only the time necessary for the magnet 139 to attract the armature 133. In the meantime the bimetallic strip 123, because of its resistance and the flow through it of the current to both the running and starting windings, has 10 started to heat and bend towards the contact 142. After the normal starting period of the motor, the contact 142 engages the contact 143, which thus shunts the electromagnet 139 and permits the armature 133 to drop and open the starting lead and deenergize the starting winding. When the contacts 142 and 143 are brought together and the running winding has been cut out, the amount of current flowing through the device 123 is reduced to the normal running requirements of the running winding. The device 123 is so calibrated that this current is insufficient to maintain the contacts 142, 143 closed and they begin to open as soon as the starting winding is cut out. The normal running current then flows through the magnet 139, but the magnet is so calibrated that it does not attract the armature 133 under these conditions, and hence the motor continues to run as long as desired with the running winding only.

In order to change the structure of Figs. 3 to 7 so that it may form the circuit shown in Fig. 1, it is only necessary to move the wire 170 from the post 128 to a post 160 as indicated by a dotted line at 170a on the strip 122, the other connections remaining as previously described. When so connected, current from the main line flows through the wire 158, strip 105, contact 107, strip 114, contact 116, resistance 120, strip 122, wire 170a, electromagnet 139, wire 171, post 126, and wire 163 to the running winding from whence it returns to the common lead line of wire 162, post 161, and wire 160 to the main line. A relatively large or surge current flows through this circuit to the running winding, because the motor is stationary, and the magnet calibration is such that it causes the armature 133 to spring upwardly and close the contacts 128 and 130. This closes the starting lead line, which in this case includes the U-shaped bimetallic member 123, strip 125, contact 128, armature 133, contact 130, strip 129, post 131, and wire 164 leading to the starting winding from whence the current returns through the wire 162, post 161, and wire 160 to the main line. The current flow to the starting winding passes through the bimetallic strip 123 and its calibration is such that this current causes it to heat and close the contacts 142 and 143 which shunts the electromagnet 139 because of the relatively small resistance of the bimetallic member 123. When the electromagnet 139 is shunted, the armature 133 retracts and opens the contacts 128 and 130 thus opening the starting lead line and deenergizing the starting winding. When this occurs only the normal running winding current flows through one leg of the bimetallic strip 123, but the calibration is such that this is insufficient to heat the strip to the point where it maintains the contacts 142 and 143 closed and therefore these contacts open. The normal running current then passes through the electromagnet 139;

but the calibration is such that this current is not sufficient to move the armature 133 upwardly and close the contacts 128 and 130.

The elements of Figs. 3 to 7 inclusive will be readily identified as corresponding to certain elements shown in Figs. 1 and 2 and need not be specifically compared. The permanent magnet 110 has not been shown in Figs. 1 and 2 and is used merely for the purpose of providing a snap action when the arm 108 is moved upwardly away from the contacts 107 and 116 as will be readily understood, the spring and loose connection of the pin 113 providing the necessary play to prevent arcing when the arm 108 is moved.

While in the preferred embodiment, the timing devices 28 and 52 are so calibrated that they shunt the electromagnets every time that the motor is started, yet it is within the purview of this invention that these timing devices can be used merely as protective or safety devices for the usual surge current starting relay heretofore commonly used. Thus in Fig. 1, the electromagnet 25 may be so calibrated that it attracts the armature 31 when the starting surge current flowing to the running winding passes through it, but releases the armature because of the decrease in current when the motor has attained sufficient speed so that it can attain its normal running condition. This type of starting relay can be calibrated for the lowest likely voltage to be encountered during normal operation. Such a relay when so calibrated, however, is likely to fail to function when unusually high voltages are encountered. When such voltages are encountered, the current flowing to the running winding does not drop sufficiently after the motor has attained its starting speed to release the armature 31 and thus the starting winding is not cut out as long as the high voltages continue. The device 28, under these conditions of high voltage, can be used as a safety device and can be so calibrated that it starts to but does not close the contacts 42 under the normal or low voltages heretofore described, but that it will close the contacts 42 after the termination of the normal starting period and after failure of the armature 31 to drop during high voltages. Thus under such use of my invention, the timing device 28, while it still does shunt the electromagnet occasionally after the starting period, is used merely as a safety device which closes the contacts 42 only when the voltages are high enough to prevent the armature 31 from functioning normally.

Likewise the device 52 of Fig. 2 can be used merely as a safety device to operate only under the high voltages just described with respect to Fig. 1. In this case the electromagnet 59 can be so calibrated that for low or normal voltages it attracts the armature 64 by the running surge current during the starting period of the motor, but releases the armature when the running winding current drops after the motor has attained its starting speed. When high voltages are encountered, and the armature 64 fails to drop, the device 52 responds as a safety device and closes the contacts 53 to shunt the magnet 59 and permit the armature 64 to drop and thus cut out the starting winding 17. The electromagnet is then unable to reclose the starting contacts even under such high voltages. It is to be understood that such use of the timing devices 28 and 52 merely as safety devices as above described comes within the purview of my invention.

While the form of embodiment of the invention as herein disclosed, constitutes a preferred form, 75

it is to be understood that other forms might be adopted, all coming within the scope of the claims which follow.

What is claimed is as follows:

- 5 1. Refrigerating apparatus including a compressor, condenser, and evaporator connected in a closed circuit, said closed circuit having a continuously open restricted connection between the condenser and evaporator for controlling the flow of refrigerant to the evaporator during the operation of the compressor, and for equalizing pressures within the system to unload the compressor when the compressor is idle, an electric motor and electric circuit for operating the compressor, means in the electric circuit for stopping the energization of the electric circuit when the pressures within the closed refrigerant circuit have not equalized sufficiently to permit starting of the electric motor and after a period of rest again energizing the electric circuit, and means responsive to the temperature of the evaporating means for controlling the energization of the electric motor.
- 10
- 15
- 20

2. Refrigerating apparatus including a compressor, condenser, and evaporator connected in a closed circuit, said closed circuit having a continuously open restricted connection between the condenser and evaporator for controlling the flow of refrigerant to the evaporator during the operation of the compressor, and for equalizing pressures within the system to unload the compressor when the compressor is idle, an electric motor and electric circuit for operating the compressor, means in the electric circuit for stopping the energization of the electric circuit when the pressures within the closed refrigerant circuit have not equalized sufficiently to permit starting of the electric motor and after a period of rest again energizing the electric circuit, and a switch for stopping and starting the motor in accordance with the temperature produced by the refrigerating apparatus.

GEORGE C. PEARCE. 20
